WINDOW BOX

Hulda C. Martin, Milldale, Conn.

Application February 16, 1939, Serial No. 256,782

4 Claims. (Cl. 47—36)

This invention relates to window boxes, and more particularly to an extensible window flower box.

One object of this invention is to provide a flower box of the above nature which will be adjustable to fit the window ledge upon which it is to be placed.

Another object is to provide an extensible two-part flower box having a U-shaped gasket to seal the parts together to prevent the leakage of water therefrom.

A further object is to provide improved clamping means for holding parts of the extensible window box together.

15. A still further object of this invention is to provide an improved window box of the above nature which will be relatively inexpensive to manufacture, simple in construction, compact, ornamental in appearance, and very efficient and durable in use.

With these and other objects in view, which will appear as the description proceeds, there have been illustrated in the accompanying drawings several forms in which the invention may be conveniently embodied in practice.

In the drawings:

Fig. 1 illustrates one form of extensible window box in which the principles and features of this invention are embodied.

30. Fig. 2 is an enlarged sectional view taken on the plane 2—2 of Fig. 1.

Fig. 3 is a detail face view of the means for clamping together the parts of the box shown in Fig. 1, looking in the direction of the arrow 3 in Fig. 2.

35. Fig. 4 illustrates another form of extensible window box.

Fig. 5 is an enlarged sectional view through a portion of the box, taken on the line 5—5 of Fig. 4 to show the clamping means for holding the box sections in adjusted position.

Fig. 6 is a detail face view of the same.

Fig. 7 is a sectional view similar to Fig. 5, showing a modified form of box clamping means.

40. Fig. 8 is a similar section showing still another form of box clamping means.

Referring now to the drawings wherein like reference numerals designate like parts throughout the several views, the numeral 10 (see Figs. 1—3) denotes the outer section, and the numeral 11 the inner section of an extensible metallic window box embodying the features of this invention. The outer section 10 has an end member 12 and a pair of side members 13 and 14, all of which are provided with outwardly rolled upper edges

15. The inner section 11 has a closed end member 16 which is provided with an outwardly rolled edge 17, and side members 18 and 19 having their upper edges 20 turned in their entire length, or at least adjacent the open end 21 thereof, to form a downwardly directed shoulder 22. The outer and inner sections 10 and 11 are provided with holes 23 and 24, respectively, in each of their respective side members adjacent their respective and members 12 and 21 to receive a chain or 10 cord 25 which is adapted to pass over hooks 26 and 27 formed on the ends of a pair of telescoping supporting bar members 28 and 29, respectively.

The bar member 28 is generally U-shaped in 15 cross-section and is adapted to slide within the bar member 29, which is similarly shaped. Three supporting screws 30 are provided to secure the telescoped bar members 28 and 29 to any suitable stationary part of a window frame or wall (not shown), said screws being adapted to pass through the bar members 28 and 29. The center screw 30 passes through the outer bar member 29 and through an elongated slot 31 formed in the bar member 28 and serves to lock the members 23 20 and 29 together in adjusted position.

In order to seal the jointure between the box sections 10 and 11, provision is made of a U-shaped gasket 32 in the form of a narrow strip of rubber or like yieldable material, which is 30 wrapped about the bottom and side walls of the inner box section 11 adjacent its open end,—the ends 33 and 34 of the gasket 32 being folded inwardly and downwardly over the upper shoulder 22. After the gasket 32 has been so applied to 35 the inner box section 11, this section is pressed downwardly into the outer box section 10 and adjusted with respect thereto to form the desired length of box. The two sections 10 and 11 will then be clamped together at their upper edges to 40 secure the box sections 10 and 11 tightly together. The clamp comprises a metallic member having a flat top portion 35, a hook-shaped end portion 36 adapted to fit around the rolled edges 15 of the side members 13 and 14 of the part 10, 45 and a flat vertical portion 37 extending downwardly along the side members 18 and 19 of the section 11 to a point below the shoulder 22. The lower end of the portion 37 is bifurcated to receive a catch member 38, which is hinged there- 50 to by a pin 39.

The catch member 38 is provided with a lip 40, which may be toothed, if desired, and a finger actuating piece 41 extending substantially at right-angles therefrom, and said catch member 55

38 is so mounted on the portion 37 of the clamp member that when the finger piece 41 is pressed downwardly into the full line position shown in Fig. 2, the lip 40 will engage and press the ends 33 and 34 of the gasket 32 against the side members 13 and 14 of the part 11 below the shoulder 22 to draw the top portion 35 downwardly and to press the parts 10 and 11 together sidewise.

In the forms shown in Figs. 4, 5 and 6, the window box may be constructed of wood, glass or porcelain, or other suitable material, and may be arranged to provide three compartments 42, 43 and 44 to hold various articles, such as potted plants, gold fish and chemically-grown plants, respectively. In the bottoms of each compartment 43 and 44, drain apertures 45 and 46 are provided and are stopped by corks 47 and 48, respectively.

The outer box section 49, in this instance, is closed at its end 50 and has side members 51 and 52, each being provided with holes at their ends for receiving a chain or cord 53. The inner box section 54 is preferably closed at each end 55 and 56 and has side members 57 and 58. A partition 59 is provided intermediate the ends 55 and 56 of the box section 54 to form a pair of compartments 42 and 43 in the inner box section. A U-shaped gasket 60 formed of rubber or like material, and similar to the gasket 32 of the first form, is provided and is wrapped about the sides and bottom of the inner section 54 adjacent its closed end 55 with its upper ends 61 and 62 overlapping the upper edges of the side members 51 and 58 and extending downwardly on the inside a short distance.

The outer and inner box sections 49 and 51 are clamped together by means of a clamp member comprising a flat top portion 63, a flat vertical portion 64 extending downwardly along the outside of the side members 51 and 52 of the outer part 49, and a short bifurcated portion 65 extending downwardly along the inside of the side members 57 and 58 of the inner part 54 and over the gasket ends 61 and 62. A catch member 66 disposed in the bifurcated portion 65 and pivoted thereto by a pin 67 is also provided, and as in the previous form has a lip 68 and a finger actuating piece 69 extending substantially at right-angles thereto. The lip 68 presses against the gasket end 61 or 62 and forces the respective side members of the box parts 49 and 54 together laterally when the finger piece 69 is pressed downwardly into the full line position shown in Fig. 5.

An inverted U-shaped clip 70 is secured by a horizontal rivet 70a flush with the upper edge of the side members 51 and 58 of the inner section 54 directly below the gasket 60. A vertical threaded bolt 71 having its head 72 disposed below the clip 70 extends upwardly through said clip, the gasket 60, and an elongated opening 73 provided in the top clamp member portion 63. A wing nut 74 threadingly engages the bolt 71 to force the portion 63 downwardly against the gasket 60 to compress the latter and to secure the clamp member to the inner box section 54.

In the modified form of clamp shown in Fig. 7, a vertical end portion 75 is secured, as by a horizontal screw 76, to the side member of the outer box section 77. A horizontal top portion 78 is pivoted to the upper end of the vertical portion 75 by a hinge pin 79, and said top portion extends over the upper edges of the side members of both the outer and inner box parts 77 and 80 respectively. The portion 78 is spaced slightly

above the upper edge of the outer box part 77, but is adapted to rest on the portion of the gasket 81 overlying the upper edge of the box part 80.

The top portion 78 of this form of clamp is bent downwardly at 82 along the inside of the inner box section 80, and has a catch 83 pivoted thereto by a hinge pin 84. The catch 83 has a lip 85 extending at right-angles thereto to engage the gasket end 86, and is also provided with a finger actuating piece 87 which is adapted to overlie the top portion 78 when it is swung into the locking position shown in Fig. 7. In the operation of this clamp, the lip 85 will be forced downwardly upon the gasket end 86 to draw it taut, as well as to force said gasket to draw the box sections 77 and 80 toward each other to compress the portion of the U-shaped gasket 81 therebetween and to seal said box sections together.

In the form of clamp shown in Fig. 7, an inverted U-shaped clip 88 is riveted flush to the upper edge of the outer box part 77, and embraces a vertically disposed bolt 89 which passes upwardly therethrough and through the top portion 78 of the clamp member. By turning a wing nut 90 downwardly along the bolt 89, the top portion 78 of the clamp member will be urged downwardly against the gasket 81, and the inner box section 80 will be forced downwardly to compress the gasket 81 between the bottoms 91 and 92 of the box sections 77 and 80 to seal said sections together.

In the form shown in Fig. 8, the clamp member has a vertical flat portion 93 extending downwardly along the outside of the side member 94 of the outer box section, a top flat portion 95 extending over the upper edges of the side member 94 and of the side member 96 of the inner box part, and a flat portion 97 extending downwardly along the inside of the side member 96. The portion 93 is secured to the side member 94 by a horizontal rivet 98, and the downturned portion 97 is bifurcated to receive a pivoted catch member 99, similar in form and operation to the catch member 66 described above in respect to Figs. 4, 5 and 6.

A thumb screw 100 is provided and is passed through the top portion 95 of the gasket 101 and has its end 102 engaging the upper edge of the side 50 96 of the inner box section. Actuation of the thumb screw 100 will press the inner box section downwardly in respect to the outer box section to compress the gasket 101 between the bottoms 103 and 104 of the outer and inner box 55 parts respectively.

Operation

In all instances, the U-shaped yieldable watertight gasket is wrapped about the lower edge of 60 the inner box part adjacent the end thereof which is to be telescoped within the outer box part. The clamp member selected for use is then placed in position and the finger piece thereof actuated to force the lip thereof in locking 65 position. Where a bolt or thumb screw is provided, this will, of course, be tightened before the finger piece of the clamp is actuated.

While there have been disclosed in this specification several forms in which the invention 70 may be embodied, it is to be understood that these forms are shown for the purpose of illustration only, and that the invention is not to be limited to the specific disclosures, but may be modified and embodied in various other forms 75

without departing from its spirit. In short, the invention includes all the modifications and embodiments coming within the scope of the following claims.

5 Having thus fully described the invention, what is claimed as new and for which it is described to secure Letters Patent, is:

- 10 1. In an extensible window box, an outer part, an inner part adapted to telescope within said outer part, a water-tight gasket between said parts, and releasable clamping means to press said parts together to compress the gasket therebetween and seal them together.
- 15 2. In an extensible window box, an outer box part having side members provided with rolled top edges, an inner box part having side members and telescoping within said outer part with its side members lengthwise overlapping the side members of said outer part, a rubber gasket located between the adjacent ends of said parts, and a clamp member having a hooked portion shaped to engage the exterior of the rolled top edge of said outer part, and said clamp having a catch swingable into position to press the side members of said inner part toward the side members of said outer part to compress said gasket therebetween.
- 20
- 25

3. In an extensible window box, an outer part having side members provided with outwardly rolled top edges, an inner part having side members which telescope within said outer part with its side members lengthwise overlapping the side members of said outer part, a yieldable water-tight gasket between the side members of said parts, and a clamp member having a hooked portion to engage over the rolled top edge of said outer part, the side members of said inner part having downwardly directed shoulders thereon, and a clamping catch having means to cooperate with said shoulders to draw said parts together and compress said gasket therebetween.

4. In an extensible window box, an outer box part having side members and a bottom, an inner box part also having side members and a bottom and being adapted to telescope within said outer part, a gasket between the bottom and sides of said box parts, releasable means to press said inner part downwardly to compress the gasket between its bottom and the bottom of said outer part, and releasable means to press the sides of said parts together to compress the gasket therebetween.
